UNITED STATES PATENT OFFICE.

JOHN S. MONAGHAN, OF ROCHESTER, NEW YORK, ASSIGNOR TO GERMAN-AMERICAN
BUTTON COMPANY, OF ROCHESTER, NEW YORK, A CORPORATION OF NEW YORK.

DESIGN FOR A BUTTON.

50,844.

Specification for Design.

Patented May 29, 1917.

Application filed March 23, 1917. Serial No. 157,031. Term of patent 3½ years.

To all whom it may concern:

Be it known that I, JOHN S. MONAGHAN, a citizen of the United States, and a resident of Rochester, Monroe county, State of New York, have invented a new, original, and ornamental Design for Buttons, of which the following is a specification.

My design is represented in the accompanying drawing, in which:

Figure 1 is a plan view of a button showing my new design.

Fig. 2 is a side elevation looking in the direction of the arrow 2 in Fig. 1.

Fig. 3 is a side elevation looking in the direction of the arrow 3 in Fig. 1.

The button is circular and is provided with a raised base, the upper exposed surface of which is curved. Projecting from the center of the base is a cylindrical por-

tion the diameter of which is less than that of the base. Mounted on this projection is another cylindrical form of substantially the same diameter, and the top of which is flat and hexagonal in shape. From each side of this hexagonal center flat surfaces extend downwardly and outwardly.

I claim—

The ornamental design for a button substantially as shown and described.

In witness whereof I have hereunto set my hand at Rochester, in the county of Monroe and State of New York this 15th day of March 1917.

JOHN S. MONAGHAN.

In presence of—

ERNEST BROWN,
GERTRUDE M. HILLER.
